UNITED STATES PATENT OFFICE

2,472,735

BAROMETRIC INSTRUMENT

Carl J. Ulrich, Minneapolis, Minn.

Application September 12, 1945, Serial No. 615,764

9 Claims. (Cl. 73—385)

1

This invention relates to a scientific or laboratory instrument comprising a member having a heavy liquid such as mercury therein and tubes connected to said member adapted to contain atmosphere or another gas. Said instrument may comprise a barometer or a device for demonstrating certain laws of gases, such as Boyle's law or Charles' law. Such instruments usually comprise a member having a chamber with heavy liquid such as mercury therein with means for reducing the volume of said chamber to cause movement of said mercury. One form of such a member used comprises a diaphragm with means for moving the same to cause movement of said mercury. Such prior instruments have been found very faulty in operation. Where a diaphragm is used, the same loses its resiliency and after the instrument has been used for some time it is very difficult to adjust the same.

It is an object of this invention to provide a simple, efficient and easily operated structure for such an instrument.

It is a further object of the invention to provide such an instrument as above set forth in which a tube of resilient material such as rubber is used to contain the heavy liquid or mercury, together with means for compressing portions of said tube to cause movement of said liquid or mercury.

It is still further an object of the invention to provide such an instrument comprising a tube of resilient material such as rubber having upwardly extending spaced portions connected at their lower ends, a heavy liquid such as mercury in said tube, rigid tubes such as glass tubes connected to the upper ends of said portions, together with adjustable means for compressing said resilient tube to cause movement of the mercury therein.

It is more specifically an object of the invention to provide a device comprising a tube of resilient material, preferably of U-shape, a body of heavy liquid such as mercury in said tube, rigid tubes such as glass tubes connected to the upper ends of said resilient tube, a rigid block having a groove in which said resilient tube is disposed, a member adjacent said block having projecting means thereon aligned with said groove, and means such as a screw with a convenient handle thereon for moving said member toward said block to compress said resilient tube and cause movement of the mercury therein.

These and other objects and advantages of the invention will be fully set forth in the following description made in connection with the accom-

2

panying drawings in which like reference characters refer to similar parts throughout the several views and in which:

Fig. 1 is a view in front elevation of one form of the device;

Fig. 2 is a view in front elevation with certain parts removed;

Fig. 3 is a horizontal section taken on line A—B of Fig. 1;

Fig. 4 is a horizontal section taken on line C—D of Fig. 1;

Fig. 5 is a horizontal section taken on line E—F of Fig. 1;

Fig. 6 is a view in front elevation of a different form of instrument; and

Fig. 7 is a view in front elevation of still another form of instrument.

Referring to the drawings, particularly Figs. 1 to 5, an instrument is shown comprising a supporting member 10. Said member 10, as shown in Figs. 1 and 2, is of elongated form, the same having rounded upper and lower ends and the same is substantially rectangular in transverse cross section. On its front side member 10 is provided with a pair of grooves 10a, which grooves are joined at their lower ends by a semi-circular portion 10b. A tube 12 is provided, which tube is substantially of U-shape, the same having upwardly extending parallel portions which are connected at their lower ends by a semi-circular portion. Tube 12 is disposed in the slots 10a and the connecting portion 10b thereof. Tube 12 will be made of some resilient material such as rubber or a rubber composition. A rigid tube 13, which preferably will be made of glass, has its lower end received in one of the upper ends of tube 12 and this tube 13 extends upwardly to adjacent the top of member 12 and is also disposed in one of the grooves 10a, as shown in Fig. 3. Tube 13 will

have a closed upper end. A scale 14 is formed on member 10 adjacent the upper end of tube 13 and the same is provided with graduations which will be provided with appropriate designations such as numerals indicating inches of mercury, as shown in Fig. 1. Another rigid tube 15 is secured in the upper end of the other part of tube 12 and extends upwardly a short distance therefrom. Tube 15 will also preferably be made of glass and the same is disposed in the other groove 10a. Tube 15 will be open at its upper end. Tubes 13 and 15 can very conveniently be inserted in the ends of the resilient tube 12 and may also be secured therein by some adhesive. Tubes 13 and 15 are held in place on member 10 by a transversely extending clamping member or

cleat 16 secured to member 10 by the spaced screws 17. Tube 13 is further secured to member 10 by a small cleat 19 secured to member 10 by spaced screws 21. A member 18 is disposed adjacent the front of member 10 at its lower end, the same having a flange 18a which extends along the sides of member 10 as well as around the lower end thereof. Member 18 is thus in front elevation of the same general shape as the lower end of member 10. Member 18 has formed thereon a pair of projections or ribs 18b which extend downwardly and are connected at their lower ends by a semi-circular portion so that they aline with and can move into the grooves 10a and portion 10b thereof. A block 20, which preferably will be made of metal, is fitted into member 10 at the rear side thereof, the same having a flange 20a through which attaching screws 24 pass. A screw 23 is threaded into block 20, the same extending through an opening 18c in member 18 and also extending through a portion of member 10. Screw 23 is provided with a handle 25 shown as in the form of a small hand wheel, which preferably will have a knurled periphery. Wheel 25 has a reduced portion 25a having a surface adjacent member 18 and adapted to engage member 18.

The tube 12 will contain some heavy liquid such as mercury. The device shown in Figs. 1 to 5 forms a barometer. Member 10 is provided with a graduation or zero mark 26. When a reading is to be taken handle 25 will be turned to move screw 23 and adjust the pressure of member 18 against tube 12 to bring the mercury therein just up to the zero mark 26. It will be seen that when wheel 25 is turned to move member 18 against tube 12 that the mercury in tube 12 will be caused to move upwardly into tubes 13 and 15. When wheel 25 is turned so that member 18 can move away from tube 12, said tube will tend to expand to its normal or fully expanded condition and the mercury will drop in tubes 13 and 15. When the mercury has been adjusted so that it is at the zero mark 26 in tube 15, a barometric reading can then be made on scale 11.

In Fig. 6 the invention is embodied in a device which is used for illustrating Boyle's law. In this structure a base member 30 is used which will preferably be in the form of a tripod having lugs 30a at the ends of its legs through which supporting screws 31 are threaded, the same being provided with adjusting wheel-like heads or handles 31a. Member 30 has a central hub 30b which is bored to have fit therein a stem 32a of a supporting member 32. Supporting member 32 will otherwise be identical with member 10 already described except that the grooves 32b formed therein corresponding to grooves 10a will extend upward to the upper end thereof, which upper end extends at right angles to the sides of member 32 instead of being rounded as is the upper end of member 10. Tubes 33 and 34, which will preferably be made of glass, are secured to the upper ends of tube 12 which will be provided, as shown in Figs. 1 to 5, and these tubes are disposed in the grooves 32b and extend to the top of member 32. Tubes 33 and 34 are held in place on member 32 by the cleat 16 already described, and a cleat 36, extending over said tubes and secured to member 32 by spaced screws 37. A scale 38 is formed on member 10 between tubes 33 and 34 having a zero mark disposed substantially at the top of member 10, said scale being numbered in units of ten upward from said zero mark. A member 40 is slidable on member 32 and over tubes 33 and 34, the same having a

transverse mark or small member such as a fine wire or hair 41 extending transversely thereof and substantially centrally vertically thereof. The top of the tube 34 will be closed and the top of tube 33 will be open.

As before stated, tube 12 will contain a heavy liquid such as mercury. Boyle's law is broadly to the effect that the volume of a gas varies inversely as the pressure. In using the instrument shown in Fig. 6, hand wheel 25 will be turned to move member 18 until the mercury in both tubes 33 and 34 is at the zero mark on the scale 38. Hand wheel 25 will then be turned to move member 18 toward member 10 to compress tube 12 and force the mercury upwardly in tubes 33 and 34. Member 40 can then be moved so that the mark 41 is at the top of the mercury in the tubes and the height of the mercury in each tube can be read. The reading in the tube 34 will indicate the volume of the gas in the upper end of said tube and the reading in the tube 33 will indicate the pressure. It can then be shown that the volume varies inversely as the pressure.

In Fig. 7 invention is shown embodied in another form of instrument which may be used to demonstrate Charles' law. This instrument is identical with the one shown in Fig. 6 as far as the parts including member 32 are concerned. Tube 12 is used, as already described, and glass tubes 43 and 44 are secured in the upper ends thereof and disposed in the grooves 32b. A casing 46, illustrated as of cylindrical form is provided, and the same has a supporting lug 47 secured thereto as by spaced screws 48. The lug 47 is apertured to have extend therethrough a supporting rod or standard 49 which will be connected at its lower end in any suitable manner to base member or tripod 30. The position of casing 46 on rod 49 can be varied and said casing held in the desired position by a headed screw 40 threaded into lug 47 and engaging rod 49. Casing 46 has a cylindrical chamber therein and inlet and outlet pipes 51 and 52 respectively are secured to casing 46 adjacent the top and bottom thereof and communicate with said chamber. A rigid tube 54 which preferably will be made of glass, is secured to the upper end of tube 44 by some simple connection such as the rubber tube 55. Tube 54 extends through the side 50 of casing 46 and is connected to a smaller casing 57 which will be made of rigid metallic material such as copper. Casing 57 has a drain tube 57a at its lower end which will be provided with some simple form of closing clamp 58. Casing 46 has an opening at its upper end extending through a spout 46a and a thermometer 60 will extend through said opening and into the chamber in casing 46 and will be sealed in said casing. Member 40 is provided, as already described, in connection with Fig. 6, and the scale 38 will also be provided, as described in connection with Fig. 6. The top of tube 43 will be open.

The instrument shown in Fig. 7 is used to illustrate Charles' law or that the pressure of the gas varies as the absolute temperature or that with a fixed volume of gas the pressure decreases with a fall in temperature and increases with a rise in temperature. The tube 12 will contain mercury, as already described. The mercury will be adjusted to stand at a certain point in the tube 44, such as mark 61. This will be done with the apparatus at room temperature, which temperature will be recorded. The height of the mercury in tube 43 will be read and recorded. The chamber in casing 46 will now be filled with small

pieces of ice and the temperature of casing 57 and the gas therein will be brought substantially to the freezing point. It will be seen that the gas in casing 57 is in communication with tube 44 and hence in communication with the mercury in tube 12. The gas in casing 57 was initially at room temperature and when it falls to freezing temperature its volume will diminish and the mercury will rise in tube 44. The mercury will now again be adjusted in tube 44 to bring it into register with mark 61. This can be done by rotating hand-wheel 25 in a counter-clockwise direction thus relieving pressure on tube 12. When the mercury has again been brought to register with the mark 61, another reading will be taken on tube 43 and this will be recorded. The chamber in casing 46 will now be filled with steam. The steam can be admitted to said chamber through the spout or pipe 52 and can pass from said chamber through the spout or pipe 51. When the chamber in casing 46 has been filled with live steam, the temperature of the gas in casing 57 will be brought to 212 degrees F. or to the boiling point. The volume of the gas in casing 57 will thus increase. The increased volume of gas will cause the gas to pass into tube 54 and the height of the mercury in tube 44 will be lowered. The mercury will now again be adjusted by turning hand-wheel 25 in a clockwise direction and compressing tube 12. The mercury will thus be forced to rise in tube 44 and it will be brought to position to register with mark 61. When the mercury is thus stationary at mark 61 another reading on tube 43 is taken. The height of the mercury in tube 43 will show the pressure of the gas. Since the upper end of tube 43 is open, the pressure indicated by the mercury therein will of course have the pressure of the atmosphere added thereto. The various readings taken with the temperature of the gas in casing 57 at different temperatures will show that as the temperature of the fixed volume of gas rises the pressure also rises. There will always be a fixed volume of gas in casing 57 and tube 54 when the mercury is stationary at the point 61. The law that the pressure decreases with a decrease in temperature and rises with an increase in pressure can thus be nicely demonstrated.

From the above description it will be seen that I have provided a simple, efficient and easily operated structure of instrument which can be used as a barometer or to demonstrate certain laws of gases. The resilient tube 12 is very easily procured and the compression and variation made in the same is easily done and the operation is very successful. Connections to the tube can be easily made and the glass tubes can be readily removed when desired. A very fine and accurate control can be had on the mercury by compressing tube 12 to reduce or increase the volume of the chamber therein. Several very troublesome objections encountered in previous structures of similar instruments have been overcome. The device, as stated, is quite simple, can be easily and inexpensively made and, as stated, very easily operated. The instruments have been amply demonstrated by actual use in laboratories and have been found to be very successful and efficient.

It will, of course, be understood that various changes may be made in the form, details, arrangement and proportions of the parts, without departing from the scope of applicant's invention, which generally stated, consists in a device

capable of carrying out the objects above set forth, in the parts and combinations of parts disclosed and defined in the appended claims.

What is claimed is:

- 5 1. An instrument dealing with gases having in combination, a tube of resilient material having substantially parallel upwardly extending portions, said portions being connected at their lower ends, a heavy liquid in said tube, a rigid transparent tube connected to one end of one of said portions and extending upwardly therefrom, a second rigid transparent tube connected to the other of said portions and extending upwardly therefrom, a member having parts adapted to engage said portions of said first mentioned tube at one side thereof rigid stationary means at the opposite sides of said portions, and means for moving said member toward said portions and stationary means for compressing the same and causing said liquid to rise in said portions.
- 10 2. A device of the class described having in combination, a U-shaped tube of resilient material having the spaced portions thereof extending substantially vertically, a heavy liquid in said tube, transparent tubes secured in the upper ends of said portions respectively and communicating respectively therewith, a rigid member having a groove in which said first mentioned tube is disposed, a second rigid member having ribs thereon transversely alined with said groove and adapted to engage said tube, and means for relatively moving said members to move said ribs against said tube and cause the liquid in said tube to move upwardly therein.
- 15 3. An apparatus of the class described having in combination, a tube of resilient material having spaced upwardly extending portions, said portions being connected at their lower ends, a body of mercury in said tube, rigid transparent tubes secured in said portions respectively and communicating therewith, a rigid block having grooves in which said portions are disposed, a member movable toward said block having portions adapted to engage said portions of said first mentioned tube, and means for moving said member toward said block to compress said portions of said first mentioned tube and cause said mercury to rise therein.
- 20 4. An apparatus of the class described having in combination, a tube of resilient material having spaced upwardly extending portions, said portions being connected at their lower ends, a body of mercury in said tube, a rigid transparent tube secured in each of said portions respectively and communicating therewith, and means for compressing said first mentioned tube for causing the mercury to rise therein.
- 25 5. A resilient tube having spaced upwardly extending portions, said portions being connected at their lower ends, a body of mercury in said tube, a rigid block having a groove therein in which said tube is disposed, a member at one side of said block having a rib thereon alined with said groove and adapted to move thereinto, and a rotatable member for moving said member toward said block to compress said tube and cause said mercury to rise therein.
- 30 6. An apparatus of the class described having in combination, an elongated member substantially rectangular in transverse cross section having a pair of spaced grooves formed in one face thereof and connected at their lower ends, a tube of resilient material disposed in the lower portion of said grooves, a body of mercury in said tube, transparent tubes secured to said first mentioned

tube and extending upwardly in said grooves respectively, means for holding said transparent tubes in place, a second member adjacent the lower end of said first mentioned member having a portion alined with the lower portion of said grooves and with said first mentioned tube and rotatable means for moving said second member toward said first mentioned member and tube to compress said first mentioned tube.

7. An apparatus of the class described having in combination, a U-shaped tube of resilient material having its spaced portions extending upwardly, a body of mercury in said tube, a member having a groove formed in one side thereof in which said tube is disposed and supported, transparent tubes connected respectively to said portions and communicating therewith, a second member adjacent the side of said first mentioned member having a rib thereon alined with said groove, a nut secured to said first mentioned member, a screw passing through said second member and threaded in said nut engaging said second member, and a handle on said screw for turning the same, moving said second member and compressing said first mentioned tube.

8. A device of the class described having in combination, a U-shaped tube of resilient material having upwardly extending spaced portions, a heavy liquid in said tube, rigid transparent tubes secured in the upper ends of said portions respectively and respectively communicating therewith, a member on which said first mentioned tube is mounted, a second member having parts adapted to engage the said portions and

means for relatively moving said members to compress said first mentioned tube and cause said liquid to rise in said portions and in said transparent tubes.

9. An apparatus of the class described having in combination, a member of resilient material having upwardly extending spaced portions, said member having a chamber therein extending into said portions, a body of liquid mercury in said chamber, spaced transparent tubes secured to said portions and extending upwardly therefrom and coaxial therewith and communicating with said chamber, one of said tubes having an open upper end and the other of said tubes being much longer than said one tube and having a closed upper end, a graduated scale extending along said other tube, and means for compressing said member to cause said mercury to rise in said tubes.
